UNITED STATES PATENT OFFICE.

WILLIAM J. KENT, OF NEW YORK, N. Y.

AUTOMATIC STOP MECHANISM FOR PRESSES OR THE LIKE.

1,139,773.

Specification of Letters Patent. Patented May 18, 1915.

Application filed October 28, 1912. Serial No. 728,270.

To all whom it may concern:

Be it known that I, WILLIAM J. KENT, a citizen of the United States, residing in the borough of Brooklyn, county of Kings, city and State of New York, have invented certain new and useful Improvements in Automatic Stop Mechanism for Presses or the like, of which the following is a specification.

10 The present invention relates to stop-mechanisms for presses, more especially metal working presses, and aims to provide certain improvements therein.

15 The invention aims to provide an improved mechanism for stopping a press when an article upon which it operates, is not properly fed thereto.

It is also an aim of the invention to provide a simple and efficient mechanism of this 20 character.

The invention is shown as applied to a press for punching or swaging so-called "nibs" on toe-calks, which nibs are used in the process of fastening the calks to horse- 25 shoes.

In the accompanying drawings:—Figure 1 is a front view of so much of a press as is necessary for illustration, showing the stop-mechanism applied thereto, and with the 30 parts in normal running position; Fig. 2 is a partial view of Fig. 1 showing the parts in a position wherein the mechanism has operated to stop the press; Fig. 3 is a horizontal sectional view, and Fig. 4 is a vertical transverse sectional view of portions of the press and stop-mechanism; Fig. 5 is a detail view of one of the parts; Fig. 6 is a view of the parts in the position shown in Fig. 2, with parts broken away for clearness.

40 In said drawings, 10 indicates the plunger of a press. This plunger slides in guides 11, 11 and is connected to a main shaft 12, which latter is connected to a driving shaft 13 through intermediate gears 14, 15. In 45 the form of press illustrated, the plunger is provided with a plurality of punches or dies 16, 16 adapted to swage projections or "nib" on pieces of metal by a succession of operations. As shown, the pieces are in the form 50 of a bar 19, from which bar they are cut, as shown at 19', Fig. 3, after the swaging operation is completed, by a cutter 20 fixed to the plunger of the press.

As shown, the bar is intermittently fed between the dies by a suitable feed mechanism 21 connected to the main shaft 12 of the press. The bar may, however, be fed by hand.

As the bar is fed through the press the projections 18, which are struck up thereon by the punches or dies 16, are adapted to successively come in contact with a finger or projection 22 upon the underside of an arm 23 forming a part of the stop-mechanism. This arm is loosely pivoted at one end upon a pin 24 fixed to a projection 25 upon the bed of the press, and its pivoted end is somewhat rounded, as indicated at 26, in order that it may have a limited universal movement upon the pivot pin 24. The arm 27 70 is in fact so mounted that it may have pivotal movement in both a vertical and a horizontal plane. The opposite end of the arm 23 is preferably rounded and fits within a slot 28 in a slide-bar 29 slidably mounted 75 in a bracket 30 attached to the bed of the press. This slide-bar 29 is acted upon by a spring-pressed pin 31 which normally presses it to one side; to the right in the construction illustrated, see Figs. 2 and 3 of 80 the drawing.

The slide-bar 29 carries a projection or stop 32, which, when the slide bar is pressed to one side, as shown in Figs. 2 and 3, projects in the way of a trip lever 33 pivotally mounted upon the end of an arm or support 34 attached to the plunger 10 of the press, and normally held in horizontal position by a light spring 50.

When the bar 19 is not properly fed, one 90 of the projections 18 on the bar will either fail to come in contact with the finger 22 on arm 23, or a projection which does come in contact with the finger will fail to push the arm 23 over (to the left in Fig. 3) sufficiently to enable the arm to push the projection or stop 32 on the slide-bar 29 out of the line of movement of the trip-lever 33. The consequence of this will be that, as the press-plunger nears the limit of its upward 100 movement, one end of the trip-lever 33 will be brought into contact with the projection 32 and its other end into contact with a projection 35 upon a lever 36. Further upward movement of the plunger will thereupon 105 cause the trip-lever 33 to turn and lift the

lever 36. The lever 36 is pivoted at 37 and is provided at one end with notches 38, 39, into which a clutch-lever 40 pivoted at 41 and operating a clutch 42 or other suitable means for throwing the press into and out of operation, is adapted to engage. The clutch-lever preferably has attached thereto one end of a spring 43, which spring normally pulls upon the arm 40 in a direction 5 to unclutch the clutch. The other end of the spring 43 is attached to a bracket 44 fixed upon the press. In running condition the clutch-lever 40 is normally engaged in the notch 38 of the lever 36. Consequently when 10 the lever 36 is lifted at one end by the trip-arm 33 the notched end of the lever 36 is depressed, thereby disengaging the clutch-lever 40, which is slidably mounted in a slotted bracket 42 fixed upon the press, from 15 the notch 38, whereupon the clutch-lever 40 is pulled over by the spring 43 so as to unclutch the clutch and stop the machine. The clutch-arm 40 may be provided with an operating handle 41', which handle may be 20 jointed so that it may normally hang down 25 out of the way.

The stopping of the machine may be hastened by means of a brake 45 connected to the clutch and operated by the clutch-arm 40. 30 The projection 35 upon lever 36 may be adjustably mounted thereon so that the action of the trip-lever 33 upon the lever 36 may be timed. For this purpose the lever 36 is provided with a slot 35' in which the 35 projection 35 is adapted to be fastened.

The lever 36 is provided at either end with a handle 46, so that the clutch-arm 40 may be disengaged from the notch 38 by manually pressing down upon or lifting one of 40 the handles of the lever 36. A spring 48 is provided for lifting the notched end of the lever 36 into engagement with the clutch-arm 40. The weight of the lever 36 upon one side of its pivot may be relied upon 45 for this purpose, but a spring is provided for making the action more positive.

When the bar upon which the press operates is properly fed, and has been given its full movement, the projection 18 in engagement with the finger 22 gives the arm 23 a full movement, see Fig. 1, pressing the slide bar 29 against the pressure of the spring pressed pin 31, and thereby moving the projection 32 out of the path of the trip-arm 33. Consequently the trip-arm 33 upon the upstroke of the plunger fails to strike against the projection 32 and is thereby not thrown upwardly against the projection 35 on the lever 36, but contacts with the projection 35 on lever 36 and idly turns on its pivot against the light pressure of the spring 50. The lever 36 therefore remains in its normal position and is not caused to 60 release the clutch-arm 40. The plunger 10 65 thereby completes its upward movement and

continues its cycle of operation without having its downward course arrested.

The underside of the plunger 10 of the press is provided with a stud 52, which upon the downward stroke of the plunger, hits 70 against the heel 3 of the arm 23 and lifts it, as shown in the dotted line position in Fig. 4, thereby lifting the finger 22 from engagement with the projection 18 of the bar 19 with which it is in contact. The 75 arm 23 is then pushed over while it is in its lifted position by the spring pressed pin 31 and dropped into position to be engaged by a succeeding projection 18 on bar 19 at a 80 succeeding feeding operation, when the projection 52 moves out of engagement with the heel 3 of the arm 23 upon the upward movement of the press-head. The dropping of the arm 23 may be rendered more positive by means of a spring 54 bearing on the 85 underside of the heel 3.

While I have shown my invention as applied to one form of press, it is not to be understood to be confined thereto, but may be applied to many forms of presses, and 90 while I have illustrated and described but one embodiment of the stop mechanism, the invention is not to be understood as confined thereto, as many modifications therein may be made without departing from the spirit 95 of the invention. Furthermore, while the mechanism has been shown as operating upon a bar from which the articles are subsequently cut, the mechanism may operate upon articles in other forms, as in a separated state. 100

What is claimed is:—

1. A press having means for stopping it, a part moving in unison with the press plunger and tending to operate said stopping means, and means adapted to contact with the work fed to the press, and when displaced thereby, to render said part moving in unison with the press plunger inoperative to affect said stopping means, whereby the 110 stopping of the press is prevented when the work is properly fed.

2. A stopping mechanism for presses, comprising a clutch, means adapted to throw said clutch into and out of operation, said 115 means operating normally to maintain said clutch in operation, a part adapted to move in unison with the press plunger and tending to operate said means to throw said clutch out of operation, and means adapted 120 to contact with the work fed to the press and when displaced thereby, to render said part moving in unison with the press plunger inoperative to affect said clutch operating means, whereby the stopping of the press 125 is prevented when the work is properly fed.

3. A press having means for stopping it, and an arm for operating said stopping means, said means being normally in a position to operate the press, means adapted to 130

- move in unison with the plunger of the press, and adapted to control the operation of said arm, and means adapted to engage an article fed to the press and when displaced thereby to render the same part moving in unison with the plunger, inoperative to affect said arm, whereby the stopping of the press is prevented when the press is properly fed.
4. A press having means for stopping it, a part moving in unison with the press plunger and tending to operate said stopping means, and means adapted to contact with the work fed to the press, comprising a stop, adapted when displaced by said work, to render said part moving in unison with the press plunger inoperative to affect said stopping means, whereby the stopping of the press is prevented when the work is properly fed.
5. A press having means for stopping it, a part moving in unison with the press plunger and tending to operate said stopping means, and means adapted to contact with the work fed to the press, comprising a spring-pressed stop normally pressed into position to render said part moving in unison with the plunger operative to affect said stopping means, and adapted when displaced by said work, to render said part moving in unison with the press plunger inoperative to affect said stopping means, whereby the stopping of the press is prevented when the work is properly fed.
6. A press having means for stopping it, a part moving in unison with the press plunger and tending to operate said stopping means, an arm having a part adapted to contact with the work fed to the press, and a stop, said arm when displaced by said work, moving said stop to render said part moving in unison with the press plunger inoperative to affect said stopping means, whereby the stopping of the press is prevented when the work is properly fed.
7. A press having means for stopping it, a part moving in unison with the press plunger and tending to operate said stopping means, an arm having a limited universal movement and having a part adapted to contact with the work fed to the press, and a stop, said arm when displaced by said work, moving said stop to render said part moving in unison with the press plunger inoperative to affect said stopping means, whereby the stopping of the press is prevented when the work is properly fed.
8. A press having means for stopping it, a part moving in unison with the press plunger and tending to operate said stopping means, means adapted to contact with the work fed to the press, and when displaced thereby, to render said part moving in unison with the press plunger inoperative to affect said stopping means, whereby the stop-
- ping of the press is prevented when the work is properly fed, and means for timing the action of said part moving in unison with the plunger on said stopping means.
9. A press having means for stopping it, a part moving in unison with the press plunger and tending to operate said stopping means, means adapted to contact with the work fed to the press, and when displaced thereby, to render said part moving in unison with the press plunger inoperative to affect said stopping means, whereby the stopping of the press is prevented when the work is properly fed, and means for moving said work-contacting part from contact with work to a position to contact with succeeding work.
10. A stop mechanism for presses, comprising means adapted to throw the press into and out of operation, an arm for operating said means, means for retaining said arm in position to hold said first-named means in running position, and mechanically operating means having a part adapted to engage an article fed to the press for controlling the release of said arm by said retaining means.
11. A stop mechanism for presses, comprising means adapted to throw the press into and out of operation, a spring retracted arm for operating said means, means for retaining said arm in position to hold said first-named means in running position, and mechanically operating means having a part adapted to engage an article fed to the press for controlling the release of said arm by said retaining means.
12. A stop mechanism for presses, comprising means adapted to throw the press into and out of operation, an arm for operating said means, means for retaining said arm in position to hold said first-named means in running position, means adapted to move in unison with the plunger of the press for releasing said arm from said retaining means, and means adapted to engage an article fed to the press for controlling the operation of said releasing means.
13. A stop mechanism for presses, comprising means adapted to throw the press into and out of operation, an arm for operating said means, means for retaining said arm in position to hold said first-named means in running position, means adapted to move in unison with the plunger of the press for releasing said arm from said retaining means, a stop adapted to operate said releasing means, and means adapted to engage an article to be fed to the press for moving said stop out of position to operate said releasing means when an article is properly fed.
14. A stop mechanism for presses, comprising means adapted to throw the press into and out of operation, an arm for oper-

ating said means, means for retaining said arm in position to hold said first-named means in running position, means adapted to move in unison with the plunger of the 5 press for releasing said arm from said retaining means, a spring-pressed stop normally pressed into position to operate said releasing means, and means adapted to engage an article to be fed to the press for 10 moving said stop out of position to operate said releasing means when an article is properly fed.

15. A stop mechanism for presses, comprising means adapted to throw the press 15 into and out of operation, an arm for operating said means, means for retaining said arm in position to hold said first-named means in running position, means adapted to move in unison with the plunger of the 20 press for releasing said arm from said retaining means, a stop adapted to operate said releasing means, and an arm adapted to engage an article fed to the press for moving said stop out of position to operate 25 said releasing means when the article is properly fed.

16. A stop mechanism for presses, comprising means adapted to throw the press into and out of operation, an arm for operating said means, means for retaining said arm in position to hold said first-named means in running position, means adapted to move in unison with the plunger of the press for releasing said arm from said retaining means, a stop adapted to operate said releasing means, and an arm having a 30 projection thereon adapted to engage an article fed to the press for moving said stop out of position to operate said releasing 35 means when the article is properly fed.

17. A stop mechanism for presses, comprising means adapted to throw the press into and out of operation, an arm for operating said means, means for retaining said 45 arm in position to hold said first-named means in running position, means adapted to move in unison with the plunger of the press for releasing said arm from said retaining means, a stop adapted to operate 50 said releasing means, and an arm having a limited universal movement adapted to engage an article fed to the press for moving said stop out of position to operate said releasing 55 means when the article is properly fed.

18. A stop mechanism for presses, comprising means adapted to throw the press into and out of operation, an arm for operating said means, means for retaining said 60 arm in position to hold said first-named means in running position, means adapted to move in unison with the plunger of the press for releasing said arm from said retaining means, means adapted to engage an

article fed to the press for controlling the 65 operation of said releasing means, and means for timing the action of said releasing means on said retaining means.

19. A stop mechanism for presses, comprising means adapted to throw the press 70 into and out of operation, an arm for operating said means, a notched lever for retaining said arm in position to hold said means in running position, a trip lever adapted to move in unison with the plunger 75 of a press, a stop normally pressed into position to engage said trip lever to cause the same to operate said retaining lever to release said arm, and an arm adapted to engage an article fed to the press for moving said stop out of position to operate said releasing means when the article is properly fed.

20. A stop mechanism for presses, comprising means adapted to throw the press 80 into and out of operation, an arm for operating said means, means for retaining said arm in position to hold said first-named means in running position, means adapted to move in unison with the plunger of the 85 press for releasing said arm from said retaining means, a stop adapted to operate said releasing means, an arm adapted to engage an article fed to the press for moving said stop out of position to operate said releasing 90 means when the article is properly fed, and means adapted to move said arm from engagement with one article to a position to engage a succeeding article.

21. A stop mechanism for presses, comprising means adapted to throw the press 95 into and out of operation, an arm for operating said means, means for retaining said arm in position to hold said first-named means in running position, means adapted to move in unison with the plunger of the press for releasing said arm from said retaining means, a stop adapted to operate 100 said releasing means, an arm adapted to engage an article fed to the press for moving said stop out of position to operate said releasing 105 means when the article is properly fed, a projection carried by the head of the press adapted to lift said arm out of engagement with an article, and a spring 110 adapted to press said arm into position to engage a succeeding article.

22. In stop mechanism for presses, a lever 115 moving with the press-plunger, a stop movable into and out of operative relation with said lever, said stop being moved by the work, and means for stopping said press, said means being actuated by said lever upon coming into contact with said stop.

23. A press, a clutch, and means for operating said clutch, a reciprocating part adapted to operate said clutch-operating means, and an arm having a substantially

universal movement and having a work contacting part, said arm being movable in one plane to control the operation of said reciprocating part on said clutch-operating means, and movable in another plane to move out of engagement with the work.

In witness whereof, I have hereunto

signed my name in the presence of two subscribing witnesses.
